CLAIM

The ornamental design for a support component for toilet ladder, as shown and described.

DESCRIPTION

FIG. 1 is a front perspective view of a support component for toilet ladder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of a support component for toilet ladder shown in an environment of use.

The broken lines in the drawings illustrate portions of the support component for toilet ladder, that form no part of the claimed design. In FIG. 9, the toilet ladder shown in broken lines is environment and forms no part of the claimed design.
